UNITED STATES PATENT OFFICE.

BENJAMIN A. POST, OF OYSTER BAY, NEW YORK.

GAME APPARATUS.

Application filed September 14, 1927. Serial No. 219,500.

This invention relates to games of the nature embodying a shallow box and game pieces movable over the bottom of the box by shaking or otherwise manipulating the box.

In the present instance the bottom of the box is divided into spaces which are separated by intersecting ridges, said spaces bearing indications, such as the names of the teams of the American and National base ball leagues. The game pieces consist of two sets, one set being selective to determine the teams to be represented by each of the players and the order of play of the teams. The other set indicates the number of points or runs to be counted for the player by the teams in their order of play. The selecting set of game pieces are of contrasting color, the colors determining the order in which the teams play. The counting game pieces are of one color and of a smaller size than the selecting game pieces. The shape of the game pieces is immaterial, but it is preferred that they consist of balls so as to move easily over the playing surface, or bottom of the box.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawing hereto attached, in which,

Figure 1 is a horizontal sectional view of a game device embodying the invention on the line 1—1 of Figure 2.

Figure 2 is a vertical sectional view on the line 2—2 of Figure 1, looking in the direction of the arrows.

Corresponding and like parts are referred to in the following description and designated in both views of the drawing:

The numeral 1 designates a base or board containing the playing surface which is subdivided into spaces 2 which are preferably of square outline and separated by means of intersecting ridges 3 which are disposed to cross one another, and as a result the playing surface embodies shallow depressions or

pockets. The pockets or spaces are supplied with designations which in the present instance consist of the names of the several teams comprising the American and National base ball leagues.

For convenience the spaces or pockets are consecutively numbered from 1 to 16, both inclusive for ready determination of the spaces and the names of the teams associated therewith. A rim 4 projects upwardly from the outer edges of the base or board 1, so as to confine the game pieces and prevent loss or misplacement thereof. The shallow box thus formed is closed at the top by a transparent cover 5 of mica, celluloid, glass or other determinate material. A rim 6 secured to the sides of the box serves to retain the cover 5 in place. The rim and cover may be removable if desired to admit of access to the interior of the box for any purpose. While the ridges 3 may be provided in any manner they usually consist of strings which are stretched across the base and glued or otherwise adhesively secured thereto. These ridges define the spaces and form the pockets.

There are two sets of game pieces which are designated by the numerals 7 and 8 respectively. The game pieces 7 are of contrasting colors and are six in number, there being one of each of the colors, red, orange, yellow, green, blue and violet. These game pieces 7 select the teams for each of the players and determine the order in which the teams play. In playing the game a player shakes or manipulates the device, thereby setting the game pieces in motion, and when the game pieces come to rest one of each of the sets designated by the numeral 7 should occupy a separate space or pocket 2 and the names associated with the spaces or pockets thus occupied by the game pieces 7 determine the teams to be represented by the player. The colors of the game pieces 7 determine the order in which the teams thus selected play. It is observed that each of the players shakes or otherwise manipulates the box in turn to select the teams and their order of play. Each player jots down upon a card or sheet the names of the teams and their order of play. As indicated in Figure 1 of the accompanying drawing, the selecting set of game pieces 7 appears on the spaces 2, 4, 9, 11, 12 and 15, hence the player represents the Chicago,

New York, Washington, and St. Louis teams of the American National League, and the Boston and St. Louis teams of the National base ball league. The teams thus selected play in the order designated by the colors of the game pieces, and since the colors appear in the following order, namely, red, orange, yellow, green, blue and violet, the teams selected play in this order, which as stated, is as follows: the New York American, the St. Louis National, the Boston National, the Chicago American, the St. Louis American, and the Washington American.

15 There may be any number of game pieces comprising the set designated by the numeral 8 and these game pieces determine the number of points or runs to be scored for the team in play. The New York American being first in order of play and after the box has been shaken or otherwise manipulated and the game pieces have come to rest five of the game pieces 8 appear on the space or in the pocket representing the New 20 York American team, thus five points or runs are scored. This procedure is followed in each consecutive play, the number of game pieces 8 appearing in the space or pocket of the team in play being scored or counted for 25 the player. The player scoring the greatest number of runs or points at the end of six plays wins the game.

It is observed that the six game pieces 30 represent the six playing days of the week, hence each of the teams plays on a different day in the order designated by the colors of the game pieces 7. The game pieces are of rounding form, such as balls, to facilitate their movement over the playing surface and over the ridges 9 separating the 35 spaces or pockets. The enclosed box form of the game is preferred as it prevents loss or displacement of the game pieces in the ordinary handling of the device.

40 Having thus described the invention, I claim:

1. A game device comprising a base having a playing surface divided into spaces and having designations imprinted upon the 45 several spaces and two sets of game pieces movable over the surface of the base, the game pieces of one set selecting the spaces for the player, and the game pieces of the

other set determining the points to be scored for the space in play.

55 2. A game device comprising a base having its playing surface subdivided into spaces which are provided with designations, and two sets of game pieces movable over said surface, the game pieces of one set selecting the spaces for a player and determining the order of play of the selected spaces, and the game pieces of the other set determining the number of points to be scored by the space in play.

60 3. A game device comprising a base having its playing surface subdivided into spaces and having the spaces differently designated, game pieces of contrasting color movable over the playing surface and adapted to select the spaces to be allotted to a player, the order of play being determined by the colors, and a second set of game pieces presenting a different appearance from the 65 selecting game pieces and adapted to determine the number of points to be scored for the space in play.

70 4. A game device comprising a base, intersecting ridges subdividing the playing surface of the base into spaces or shallow so pockets, each of the spaces being differently designated, and two sets of game pieces of different size, the larger game pieces being of contrasting color to select the spaces or pockets and to determine their order of 75 play, and the smaller game pieces determining the points to be scored by the player of the space in play.

80 5. A game device comprising a shallow box provided with a transparent cover and having its bottom provided with intersecting ridges to form a playing surface subdivided into spaces upon which appear the names of the teams comprising the American and National base ball leagues, and said 85 spaces being consecutively numbered, and two sets of game pieces, the game pieces of one set serving to select the teams of a player, and being of contrasting color to determine the order of play of the teams, and the other set of game pieces determining the 90 number of points to be scored for the team in play.

95 In testimony whereof I affix my signature.

BENJAMIN A. POST.
